UNITED STATES PATENT OFFICE.

HUGH W. KIMES, OF DAYTON, OHIO, ASSIGNOR TO THE VAILE-KIMES COMPANY, OF DAYTON, OHIO, A CORPORATION OF OHIO.

DESIGN FOR A POWER-PUMP CASING.

46,222.

Specification for Design.

Patented Aug. 4, 1914.

Application filed April 12, 1912. Serial No. 690,364. Term of patent 7 years.

To all whom it may concern:

Be it known that I, HUGH W. KIMES, a citizen of the United States, residing at Dayton, in the county of Montgomery and State of Ohio, have invented a new, original, and ornamental Design for a Power-Pump Casing, of which the following is a specification, reference being had to the accompanying drawing, forming part thereof.

The figure is a side elevation of a power pump showing my new design.

I claim:

The ornamental design for a power pump casing, as shown.

HUGH W. KIMES.

Witnesses:

J. W. AIKMAN,
HARRIETT L. HAMMAKER.
